ABSTRACT: An air-conditioning distribution system in combination with a heat exchanger and blower which can be used to distribute cooled or heated air to various locations throughout a building without the use of usual ducting. By utilization of one or more distribution boxes located on the supply side of the air distribution system, air can be distributed in controlled amounts to various locations throughout the building by means of flexible tubing eliminating the necessity for metal ducting fabricated to the specific dimensional requirements of the building. By eliminating the metal ducts, a standard or modular system can be supplied which can be readily installed on the premises in accordance with the requirements of the building.

AIR-CONDITIONING DISTRIBUTION SYSTEM

BACKGROUND OF THE INVENTION

This invention relates generally to an air-conditioning distribution system which eliminates the need for prefabricated metal ducting. While not so limited, the system is especially suitable for the installation in existing buildings, and especially homes, of air-conditioning systems used for cooling. Most air distribution systems make use of metal ducts which must be prefabricated to specific dimensions with joints, elbows and other connections which will permit installation of the duct system in existing buildings or buildings under construction. Metal ducting is expensive to fabricate, especially as it cannot be mass produced. In existing buildings, installation of the ducting at specific locations and through predetermined openings compounds the problem and those in the art are well aware of the difficulties of fabricating, handling and installing metal ducting.

SUMMARY OF THE INVENTION

Generally speaking, in accordance with the invention, flexible tubing is utilized in place of metal ducting for carrying the cooled or heated air to and from the heat exchanger. In order to provide even distribution and to provide means for controlling same, one or more distribution boxes are provided on the supply side which receive air from the heat exchanger and which form junction boxes for further distribution, through flexible tubing, of the air to various locations throughout the building. The distribution boxes can be so constructed and arranged that they can readily connect to flexible tubing of various sizes and means may also be provided for controlling the flow of air to the various remote locations.

It should be noted that, while the phrase "air-conditioning" is used throughout this application, it is used in a general sense and is not intended to be limited to the cooling of air since the system can be used to distribute warm air as well as cool air and can also be used as a single system which can be changed over between warm and cool air with the change of seasons. The air supplied to the system is the function of the heat exchanger to which the system is connected, the heat exchanger, per se, forming no part of the instant invention.

Accordingly, it is an object of this invention to provide an air-conditioning distribution system of improved construction.

Another object of the invention is to provide an improved air-conditioning distribution system which eliminates the need for prefabricated metal ducting.

A further object of the invention is to provide an air-conditioning distribution system making use of distribution boxes in the delivery of air through flexible tubing.

A further object of the invention is to provide an improved air-conditioning distribution system incorporating distribution boxes of improved construction.

Still other objects and advantages of the invention will in part be obvious and will in part be apparent from the specification.

The invention accordingly comprises the features of construction, combination of elements, and arrangement of parts which will be exemplified in the construction hereinafter set forth, and the scope of the invention will be indicated in the claims.

BRIEF DESCRIPTION OF THE DRAWINGS

For a fuller understanding of the invention, reference is had to the following description taken in connection with the accompanying drawings, in which:

FIG. 1 is a schematic view of a typical air-conditioning distribution system constructed in accordance with a preferred embodiment of the instant invention;

FIG. 2 is a partial sectional view, at an enlarged scale, taken along line 2-2 of FIG. 1;

FIG. 3 is a partial sectional view, at an enlarged scale, taken along line 3-3 of FIG. 1;

FIG. 4 is a partial sectional view, at an enlarged scale, taken along line 4-4 of FIG. 1; and

FIG. 5 is a partial sectional view, at an enlarged scale, taken along line 5-5 of FIG. 1.

DESCRIPTION OF THE PREFERRED EMBODIMENT

Referring to FIG. 1, a heat exchanger is indicated generally at 11 which includes a blower 12 and may include cooling coils if the heat exchanger is used for cooling or a heater plenum if the heat exchanger is used for heating. A mixing box 13 is connected at the supply side of the heat exchanger for receiving the output from the blower. In the embodiment shown, mixing box 13 includes two outlets 14 to which are connected flexible tubes 15. Each flexible tube 15 terminates at a distribution box 16, with each distribution box including a plurality of outlets 17. Connected to a selected number of outlet 17 are flexible tubes 18, each of which terminate at a register 19.

To the return side of heat exchanger 11 is connected a return box 21 to which is connected a flexible tube 22. Flexible tube 22 is connected to a return register (not shown) to provide a return of air to the system.

If it is desired to air condition an existing house, for example, the system hereinabove described could be quickly and easily installed, all without the use of metal ducting. Heat exchanger 11 could be mounted on the floor of the attic with the cooling coils connected to an external compressor. Mixing box 13 and return box 21 is also mounted on the floor of the attic and connected to the heat exchanger. The size of the building or house to be cooled and the air flow requirements will determine the number of distribution boxes to be used. In the example shown, two distribution boxes 16 are located on the floor of the attic at spaced locations from mixing box 13. For example, one distribution box would be located at one end of the house and the other distribution box at the other end of the house. The distribution boxes are prefabricated as completed or knocked down assemblies and can be located at any convenient place within the attic. Flexible tubes 15 are connected between the mixing box and the distribution boxes and the use of the flexible tubes allows the tubes to be positioned at will and cut to length during the installation.

Registers 19 are located throughout the house for bringing the necessary amount of air into each room. On the level immediately below the attic, registers 19 may be mounted in the ceiling 23 as shown in FIG. 5. For a two or more story house, registers may be located through the walls of the lower floors or in the floor above the basement. All registers are connected to a respective one of the distribution boxes through flexible tube 18. For the registers in the ceiling, it is merely necessary to randomly position the flexible tube and cut it to length on the job. On lower floors, the flexible tube may be snaked through the walls and connected to the wall registers or maybe passed down through a central opening in the house, such as around the chimney, and connected to floor registers accessible from the basement. If desired, a large size flexible tube can communicate with a distribution box located in the basement with the distribution box being connected to the various registers through a smaller size flexible tube.

It should be noted at this point that, the location of elements in the attic is by way of example only. The system provides sufficient flexibility to locate the various elements at any convenient place throughout the house or building. Thus, a crawl space or basement is equally suitable. By utilization of the system of the instant invention, the usual limitations placed on installation of a system which uses metal ducting are completely eliminated.

For the return line, a return register is located at a suitable place and connected via flexible tube 22 to return box 21. Those skilled in the art will readily understand that the building acts as a plenum for the return system and, so long as the return system is of sufficient size to handle the air flow, the location of various return registers is substantially less critical than the location and size of the supply registers and supply lines.

A preferred construction of mixing box 13 is shown in FIG. 2. The mixing box is fabricated as a hollow cube with the usual sheet metal walls 31 and is lined with insulation 32. Outlets 14 are formed of stepped, cylindrical connectors 33 which are secured by any suitable means, such as rivets 34 to a flanged opening 35 in the walls of the mixing box. The diameter of the flexible tube to be used on any particular installation is dictated by the volume and rate of air flow required to cool or heat the building which is to receive the installation. By use of the stepped cylindrical connections, the mixing box can automatically accommodate various sizes of flexible tubing. In FIG. 2, flexible tubing 15 is shown overfitted on one portion of each connector and a suitable band 36 may be provided for clamping the flexible tube onto the connector. During the installation, the unused portions of the stepped connector 33 of smaller diameter may be cut away so as not to obstruct air flow.

A preferred construction of distribution box 16 is shown in FIGS. 3 and 4. The distribution box is also fabricated as a cube or elongated cube having walls 41 formed of the usual sheet metal with insulation 42 lining the walls. Note that the insulation, in addition to reducing heat transfer, also acts to deaden the sound of the rushing air. A plurality of stepped cylindrical connectors 43 are secured to the distribution box at flanged openings 45 through suitable means such as rivets 44. The number of outlets or connectors utilized in any particular system will depend on the requirements of the system and, for each used outlet, a flexible tube 18 is overfitted with the stepped cylindrical connector and held thereon by a band 46.

Since use of all the outlets may not be required and since it is often desirable to control the flow through used outlets, dampers may be provided in cooperation with each flanged opening 45 to completely close or selectively open the opening. As best seen in FIGS. 3 and 4, channels 47 are secured to the inner surface of wall 41 spanning opening 45. The channels slidably receive a plate 48 having a screw 49 connected thereto. Screw 49 extends upwardly through a suitable slot 51 in wall 41 and has mounted thereon a guide ball 52 and a wing nut 53. The guide ball guides along slot 51 and transmits motion through screw 49 to plate 48 to adjust the position of the plate. Wing nut 53 may be tightened to lock the plate in any desired preset position. Thus, if a particular flanged opening 45 is not to be used, plate 48 may be moved into position to completely block the opening. If the opening has a flexible tube 18 connected thereto, the plate may be moved so as to control the size of the opening. This is especially desirable for the balancing of the system after the installation has been completed in order that the proper amount of cooled or heated air is supplied to each room or location.

From the foregoing, it is apparent that the usual prefabricated sheet metal ducting is completely eliminated. With the system of the instant invention, a mixing box and a return box can be provided for connection to the heat exchanger and one or more prefabricated distribution boxes can be supplied for installation at selected locations. Thereafter, to connect up the system, it is merely necessary to utilize flexible tube suitably positioned and cut to size thereby effecting a substantial saving in time and money. While the

system of the instant invention is especially useful for installations in existing building, it can also effect a great saving in time and money when used as an installation in a building during construction.

It will thus be seen that the objects set forth above, among those made apparent from the preceding description, are efficiently attained and, since certain changes may be made in the above construction without departing from the spirit and scope of the invention, it is intended that all matter contained in the above description or shown in the accompanying drawings shall be interpreted as illustrative and not in a limiting sense.

I claim:

1. An air distribution system for buildings in combination with heat exchange apparatus including a blower comprising mixing box means for receiving air from the supply side of said heat exchange apparatus, at least one distribution box having a plurality of outlets, a flexible tube communicating between said mixing box means and each of said distribution boxes, a plurality of supply registers, a flexible tube communicating between each of said supply registers and one of said outlets, means cooperating with said distribution box for selectively controlling the flow of air through at least some of said outlets, and return box means for delivering return air to said heat exchange apparatus.
2. An air distribution system as claimed in claim 1 including at least two distribution boxes, each of said distribution boxes being located remote from said mixing box and being connected to said mixing box by a flexible tube.
3. An air distribution system as claimed in claim 1 wherein at least one of said outlets consists of a stepped connector having walls of at least two different cross-sectional sizes, said stepped connector extending outwardly from a wall of said distribution box, the cross-sectional size of the wall of said stepped connector defining the largest of said cross-sectional openings being closest to the wall of said distribution box.
4. An air distribution system as claimed in claim 3 wherein said stepped connector consists of walls defining openings of at least three different cross-sectional sizes, the wall defining the smallest of said cross-sectional sizes being located the furthest from the wall of said distribution box.
5. An air distribution system as claimed in claim 4 wherein the walls defining said stepped connector are cylindrical in cross section.
6. An air distribution system as claimed in claim 1 wherein said means for selectively controlling the flow of air through an outlet includes damper means having a slidable plate for selectively covering and uncovering a cooperating one of said outlets.
7. An air distribution system as claimed in claim 6 wherein said damper means includes a pair of channels secured to the inner surface of a wall of said distribution box surrounding said outlet, said plate being slideably received in said channels, a slot through said wall extending parallel to said channels, a control member secured to said plate and extending through said slot, and means cooperating with said control member for selectively locking said plate against sliding movement in said channels.
